SEALING APPARATUS

Frank J. Cozzoli, Plainfield, N. J.

Application September 29, 1952, Serial No. 312,011

4 Claims. (Cl. 49—7)

1

This invention relates to the art of glass working, more particularly to the art of heat-sealing ampuls and tubes containing a pharmaceutical preparation in liquid or dry form, and has for a primary objective to produce, with minimum apparatus, strong, and substantially uniform seals on containers of that kind.

In hermetic sealing of ampuls and tubes, it is customary to direct a high heat flame or fire to the region of the container where the seal is to be made, and, while holding the tube in the flame, to rotate it in the fingers in an effort to effect reasonably uniform heating and softening of the glass. While manually manipulating the tube in this manner the operator must not only watch the flame continuously, but have a steady hand so that the heat will be localized at the precise point where the seal is to be made or a one-sided or lobed seal and a weak seal will be produced. The present invention aims to reduce the eyestrain and to eliminate the need for manual holding and rotating of the tube in the fire and to produce strong and uniform seals on glass containers more quickly and efficiently.

The invention further aims to fill a need existing today for a small, simple but effective piece of apparatus for use in experimental, research or general laboratories, hospitals, and the like to seal several to a few hundred vials at a time and where production requirements do not warrant the services of a skilled glass worker or the purchase of large automtaic sealing machines.

Still another aim of the invention is to render available a versatile laboratory sealer that will conveniently handle and seal small as well as large ampuls and tubes and produce thereon uniform and strong seals of either the pull-seal or top-seal character. A single adjustment for container length in relation to the fire determines the location of the seal, and as such an adjustment is necessarily made whenever a batch is to be run, the machine of the present invention combines and embodies all the advantages of automatic pull-seal and top seal machines but without their complexities.

In attaining the objectives of the invention, it is proposed to support the ampul or tube in a V-shaped trough formed by a pair of cylinders mounted on a parallel axis and at least one of which but preferably both, is caused to rotate. In the interests of simplicity the cylinders are inclined at an angle lying within the range of 30° to 60° from a vertical plane so that an ampul placed in the V between the cylinders will by its own weight and the traction of the cylinders 55 30° and 60° from a vertical plane. Good results

2

be caused to rotate also. An adjustable shelf is provided at the lower end of the V upon which the base of the container may rest, and which shelf may be adjusted so that the upper end of the container is projected beyond the ends of the cylinders and into the fire zone. In this instance the sealing flame is supplied by a gas burner mounted upon an adjustable support, which, by manipulating a thumb screw, may be readily adjusted to position the burner tip the requisite distance from the surface of the glass. Intensity of the flame may also be controlled by throttling the fuel supply more or less as by means of hand valves or the valves on conventional mixers (not illustrated). And the entire apparatus is mounted upon a base that forms the main support for the assembly as well as housing for a small motor that drives the ampul supporting and rotating rollers.

20 Other objects and advantages will be in part indicated in the following description and in part rendered apparent therefrom in connection with the annexed drawings.

To enable others skilled in the art so fully to apprehend the underlying features hereof that they may embody the same in the various ways contemplated by this invention, drawings depicting a preferred typical construction have been annexed as a part of this disclosure and, in such drawings, like characters of reference denote corresponding parts throughout all the views, of which:

Figure 1 of the drawings is a front elevation of a sealing apparatus embodying this invention.

Figure 2 is a plan view of the apparatus illustrated in Figure 1.

Figure 3 is a side elevation of the apparatus illustrated in Figure 1.

Figure 4 is a vertical sectional view, taken substantially along lines 4—4 of Figure 1, with portions of the burner omitted.

Figure 5 is a fragmentary end view of the apparatus as it may be used to pull-seal ampuls and tubes.

45 Figures 6 and 7 are detail views of the relationship of the drive gears and of the rollers respectively.

Referring more particularly to Figures 1 and 4 50 the sealing apparatus disclosed comprises essentially an elongated hollow base 10 that is formed with a gable-type roof 11, one side 11a thereof being open. The open side 11a of the roof is pitched at a relatively steep angle lying between 30° and 60° from a vertical plane. Good results

are obtained when the pitch is on the order of 35° from the vertical, as will be explained.

A metal plate 12 is placed over the opening 11a and is suitably fastened to the base as by screws 13. The plate 12 supports a motor and gear carrier frame 14, and the latter, a geared motor 15. Screws 16, of which there are four, secure the plate 12, frame 14 and motor 15, together as a unit. The motor 15 is preferably a slow speed motor of conventional character, electrically operated, and has an output shaft 15a that projects into the frame 14. Shaft 15a is provided at its end with a drive gear 17. The gear 17 meshes with two spaced gears 18 which are carried at the ends of a pair of ampul supporting and drive rolls 19. The rolls 19 are journaled on spindles 19a that are also supported by the frame 14. Each of the rolls 19 has its lower end reduced so as to be passed through openings 12a formed in the plate 12 so that the larger diameter overlays the plate 12 and the end thrust is carried by its gear 18 resting upon a boss 14a of the motor frame.

The spindles 19a and rolls 19 are arranged on parallel axis, preferably, and project outwardly from the plate at an angle of approximately 35° from a horizontal plane in this embodiment. The adjacent peripheries of the two rolls together form a V-channel, the sides of which, when the rolls are being rotated, move in opposite directions. If a third cylindrical object is placed in the inclined channel it will of its own weight rest upon the surfaces of the rolls and by the traction of the latter be rotated also. Figures 6 and 7 illustrate diagrammatically a preferred relation of the trio of gears 17 and 18, and the pair of rolls 19 in relation to ampuls or tubes of different sizes that may be supported and rotated thereby.

As illustrated in Figures 3-5, the rolls 19 are of a length sufficient to support the body portion of long tubes without tipping, and for short tubes an adjustable shelf 20 is provided. The shelf 20 is constructed as to be supported and guided upon the front wall of the roof 11 as by a pin and slot device 21 and a clamping screw 22. The shelf 20 extends towards the rolls 19 and is formed with two crescent shaped openings 23 that receive the rolls, and a protruding tongue portion 24 that enters into the V between the rolls. If desired a back support 20a may be provided at one or both sides of the rolls 19 against which a group of unsealed or sealed tubes may rest, as indicated in Figure 2. The back rest 20a may be secured to the main plate 12 as illustrated in the drawings or may be bent up parts of the shelf 20.

In accordance with this invention, the base unit 10 also mounts and supports a means for fusing the open end of the ampul or tube. A preferred form of sealing means is illustrated more clearly in Figure 3 which comprises a burner tip 25 that is screw threaded into a T 27. The T 27 is provided with a fuel port 28 which may be connected as at 29 with a source of suitable fuel, i. e., gas, air and/or oxygen properly mixed. The T 26 and its components is mounted at the end of an end-wise adjustable support 30 that is non-rotatably journaled in a pivoted bracket 31. Bracket 31 is pivoted at 32 between a pair of flanges 33 provided by the base 10 and carries an extension 31a that straddles an adjusting screw 34. The screw 34 is screw threaded into a boss 35 in the base and carries a compression spring 36 adapted to react between the boss 35 and the inner side of the bracket extension 31a. As the screw 34 is manipulated, the bracket 31 is caused to swing

about its pivot and thereby tilt the outer end of the support 30 and the burner tip 25 toward or away from the tube or ampul that may be lying in the channel between the rolls 19. A clamp screw 37 is provided for securing the support 30 to the bracket in the desired extended position.

In a normal position, such as illustrated in full lines in Figure 3, the burner tip will direct its flame toward the tube to be sealed in a slightly upward and outward direction relative to the axis of the tube. Such an angular relation of the fire and the tube tends to direct the heat away from the contents in the body part of the tube while nevertheless concentrates the heat at the point where the seal is to be made. In Figure 3, the letter *a* indicates a small ampul positioned for sealing, with the fire adjusted for forming a top seal thereon. Letter *b* indicates the position of the top of an ampul of larger size and in which case the burner 25 will be adjusted to occupy a more outward position. Letter *c* indicates the end portion of a tube positioned for sealing and in this instance the burner is adjusted outwardly in the bracket 31, and the assembly tilted back slightly so that the fire will be concentrated properly in relation to the glass. In Figure 5, the apparatus is set up for pull-sealing a long-stemmed ampul. In this case, the fire is directed a short distance below the open end of the container. With the tube or ampul being automatically rotated as explained, the fire softens the glass at a zone below the open end and begins to form a constriction. At the proper time, the operator will draw off the tip end of the ampul with a pair of tweezers and after another moment in the flame the drawn end of the ampul is fused into a nicely rounded seal. A seal on tube *c*, in Figure 3, may be formed in similar fashion. In effecting a pull-seal, the body part of the ampul or tube may lift as the top is drawn out and to overcome this the attendant need apply only a little pressure to the body part to hold it down on its seat. With very little practice the unskilled can acquire a high degree of dexterity and efficiency in top sealing or pull-sealing ampuls and tubes or various kinds on an apparatus constructed as disclosed herein.

It will be observed that any one of the adjustments i. e. for tube diameter, tube length, or flame concentration, is readily made by manipulating a single thumb screw, and in making a complete changeover from one size to another three simple adjustments, at most, are required. It will also be noted that when the flame has been correctly located for sealing ampuls of a given length, that the angle assumed by the support 30, in relation to the axis of the ampul lying between the rolls, remains substantially constant for all sizes of ampuls and it is necessary only to lower or raise the shelf 20 and move the support 30 in or out in bracket 31 to seal an ampul of another size.

In using the apparatus, the ampul supporting shelf and the burner are adjusted to an approximate position for the seal and the burner is ignited. After the proper flame is obtained, by conventional valves or Venturi mixer (not shown), the motor switch 40 is turned on and the rolls 19 revolve. For convenience, a supply of unsealed ampuls may be placed on the shelf 20 at one side of the revolving rolls and a trial sealing of one is made. It will be found on the first ampul whether the flame is or is not properly adjusted and the necessary adjustments are made. After that, ampuls to be sealed are placed successively in the channel between the rotating

rolls where each is by its own weight and the traction of the rolls caused to revolve about its longitudinal axis with the top end projected into the fire. Rotating the ampul in this manner not only effects uniform distribution of the heat in the glass but relieves the operator of hand rotating and the constant eye concentration on the flame. Accordingly sealing time is greatly shortened, and consequently the contents of the ampul has less opportunity to heat up, the danger of an operator being burned is eliminated, and superior all around strong and uniform seals are produced.

When a seal has been produced the ampul may be lifted out of the channel between the rolls with the fingers and placed upon the shelf 20 to cool. If desired the ampuls may be caused to climb out of the channel under the power of one of the rotating rolls merely by pressing the ampul lightly against the up-coming roll which automatically causes the ampul to ride out of the channel and into the attendants fingers.

Without further analysis, the foregoing will so fully reveal the gist of this invention that others can, by applying current knowledge, readily adapt it for various utilizations by retaining one or more of the features that, from the standpoint of the prior art, fairly constitute essential characteristics of either the generic or specific aspects of this invention and, therefore, such adaptations should be, and are intended to be, comprehended within the meaning and range or equivalency of the following claims.

Having thus revealed this invention, I claim as new and desire to secure the following combinations and elements or equivalents thereof, by Letters Patent of the United States:

1. An apparatus for sealing the open ends of a filled ampul or the like comprising in combination a hollow base member having a sloping roof portion provided with an opening therein, a plate member fitted on said sloping roof portion and forming a closure for the opening therein, a motor frame carried by said plate member, a drive motor mounted to said frame and disposed within the hollow base member, said motor having a drive shaft and a drive gear mounted thereon, a pair of stationary spaced-apart spindle elements mounted in said motor frame on axes parallel to but at opposite sides of the axis of the shaft of said motor, said spindle elements projecting outwardly from the frame and substantially perpendicularly to the sloping plane of said plate, a roller element mounted for free rotation on each of said spindle elements, each of said roller elements having gear teeth in meshed relation with the gear on said motor shaft, and said roller elements being of such length and diameter that their adjacent peripheries form a sloping V-shaped trough adapted to support at least the body portion of an ampul to be sealed, ampul sealing means positioned

below and beyond the outer ends of said rollers so as to direct a sealing fire upwardly against the underside of the projecting end of an ampul supported in the sloping trough formed between the surfaces of said drive rollers, and switch means in the circuit to the motor for controlling the operation thereof and thereby the rotation of said rollers and the ampul supported in the trough therebetween.

10 2. An apparatus for sealing the open end of a filled tube, ampul or the like comprising a main support having a work surface in a plane disposed at a relatively steep angle to a horizontal plane, a pair of parallel spaced-apart spindle elements carried by said support and projecting therefrom in a direction normal to the plane of the said work surface, a drive roll element mounted for free rotation on each of said spindle elements, said roll elements forming between their peripheries a sloping V-shaped trough adapted to support an ampul in slanted position with its lower end resting upon said work surfaces, burner means positioned below and beyond the outer ends of said rollers for directing a sealing fire upwardly against the underside of the ampul that projects beyond the roller ends and outwardly and toward the open end of the ampul for effecting a sealing thereof by fusion, and means mounted to the support and connected with each of said roller elements for rotating each roller about the axis of its associated spindle to effect rotation of the ampul during the sealing thereof.

35 3. The combination of claim 2 including a supplementary support for the lower end of the ampul, and means mounting said supplementary support to the main support for adjustment in a direction axially of the roller elements, said supplementary support having portions cut away so

40 as to fit between and partially around at least the upper peripheries of said roller elements.

45 4. The combination of claim 2 including means mounting said burner means for adjustment bodily in a direction substantially axially of the roller elements but at an angle to their axis corresponding to the change in location of the point of sealing the stem ends of ampuls of different body sizes and overall lengths, and additional means for adjusting said burner generally radially of the axis of the ampul to maintain a selected spacial distance between the glass thereof and the burner.
